UNITED STATES PATENT OFFICE.

GEORGE P. TILTON, OF NEWBURYPORT, MASSACHUSETTS, ASSIGNOR TO THE TOWLE MANUFACTURING COMPANY, OF SAME PLACE.

DESIGN FOR A SPOON.

SPECIFICATION forming part of Design No. 21,742, dated August 2, 1892.

Application filed April 12, 1892. Serial No. 428,898. Term of patent 7 years.

To all whom it may concern:

Be it known that I, GEORGE P. TILTON, of Newburyport, in the county of Essex and State of Massachusetts, have invented a new and original Design for a Spoon, of which the following is a full, clear, and exact description.

Reference is to be had to the accompanying drawings, in which—

10 Figures 1 and 2 represent, respectively, the obverse and reverse of a spoon embodying my new design.

15 The design consists in the border ornamentation shown. The primary element of the border is the rose, three of which appear at the outer end in somewhat close relation, as indicated by the letters *a*, and the stems *b* range longitudinally of the handle in easy curves, forming more or less conventional 20 foliate scrolls. Repetitions of such scrolls *b'*, varied as to detail, complete the border and terminate at the base, where a rose *c* appears. Single roses *c' c''* also appear in the border on 25 opposite sides, spaced longitudinally and of unequal prominence. The three roses *a* at the end of the handle are arranged in triangular relation to each other. The reverse of the spoon is free from roses, and the foliate scrolls are substantially plain, except near 30 the end. Further, the ornamentation is confined to the border and preserves a continuous unbroken plain surface ranging substantially the full length of the handle. The detail is as follows: The separate recurring plain 35 scrolls or conventionalized stems *f f'* range longitudinally of the handle at both sides from the base of the handle toward its end, and at one side near and at the end the leafy scrolls *g g' g''* appear and present the appearance of overlapping and continuously trend-

ing in easy curves in the direction of and around the end without positive return curves at the meeting-points, each succeeding conventionalized stem or group of stems appearing as if starting from beneath the upper terminal of the one immediately inward without a pronounced or distinctive termination at the base or starting-point. The uppermost foliate scroll *g²* is continued around the top, and its leaf-like members *g³* appear as if departing directly from the conventionalized stem, and all are disposed in the general direction of the opposite side edge of the handle. A small outwardly-curved scroll *g⁴*, having both its terminals turned pronouncedly inward, appears at the said opposite side edge adjacent to the returning end of the scroll *g²*, and in connection with and outside of such scroll *g⁴* appears a short series of leaf-like figures *g⁵*. The plain scroll or conventionalized stem *f'* in the form of a compound curve appears adjacent to and inward from the small scroll *g⁴*, and a second small scroll *f²*, similar to but slightly longer than said scroll *g⁴*, appears adjacent to and inward from the scroll *f'*. The several members *g g' g² g³ g⁴ g⁵ f' f²*, as described, form the ornamentation of the broadened end of the handle as distinguished from the narrower shank of the handle, which is bordered by the scrolls *f f'*. The back of the bowl adjacent to the handle has an ornamental figure *b* of foliate members surrounding an inclosed plain surface.

I claim—

The design for a spoon, herein shown and described.

GEORGE P. TILTON.
